TWO-LEGGED BRAIDED SLING

David S. Robbins, Hamden, Conn., assignor to
The American Steel and Wire Company of New
Jersey, a corporation of New Jersey

Original application May 5, 1945, Serial No.
592,241. Divided and this application May 11,
1948, Serial No. 26,442

4 Claims. (Cl. 87—8)

1

This invention relates to a two-legged braided sling and is a division of my copending application, Serial No. 592,241, filed May 5, 1945, now Patent No. 2,448,463, dated August 31, 1948.

Two-legged braided slings are well known, but those made prior to my invention were not sufficiently flexible and the maximum strength was not obtained from the ropes used therein. In addition to these characteristics, it is desirable that the sling should lay dead.

It is therefore an object of my invention to provide a two-legged sling having these desired characteristics.

This and other objects will be more apparent after referring to the following specification and attached drawings, in which:

Figure 1 is a diagrammatic view illustrating the position of the strands prior to braiding the sling;

Figure 2 shows a braided sling assembled with the splice formed in the endless units;

Figure 3 is a view of one of the eyes with a thimble in place; and

Figure 4 is a sectional view taken on the line IV—IV of Figure 3.

Referring more particularly to the drawings, the reference numeral 2 indicates a pin around which is arranged two groups of ropes each consisting of two right and two left lay ropes. The groups are arranged around pin 2 in a substantial V-shape as shown in Figure 1. Only one pin is actually used, but for the sake of clarity two are shown. In braiding, one operator takes left lay ropes 11 and 12 in his left hand and right lay ropes 17 and 18 in his right hand and the other operator takes right lay ropes 15 and 16 in his left hand and left lay ropes 13 and 14 in his right hand. In the braiding operation, operator #1 passes his ropes back and forth in a horizontal plane keeping ropes 11 and 12 on top of ropes 17 and 18 for every reversal, or vice versa. At the same time, operator #2 passes his ropes back and forth in a vertical plane keeping ropes 15 and 16 to the left of ropes 13 and 14 or vice versa for every reversal. This operation is continued until the braiding is completed in the one leg, after which the ropes are all double spliced at 4 to make endless units. Wires 6 are arranged around the ends of the double splice as shown in Figure 2. One operator then takes left lay ropes 21 and 22 in his left hand and right lay ropes 27 and 28 in his right hand and the other operator takes right lay ropes 25 and 26 in his left hand and left lay ropes 23 and 24 in his right hand and the ropes are braided together in the same manner as the ropes in the other leg. After the braiding is completed, the ends of the ropes are spliced to

2

gether to form double splices 4. Before the braiding operation, the eight parts of rope are laid in parallel around the pin 2 and in braiding care is taken that both legs are braided from the same position. The eight parallel ropes around pin 2 are served together by means of a seven wire strand 8 and a thimble 30 is inserted in the eye 32 and strips of steel 34 are welded to the thimble to prevent it from falling out. It will be seen that the completed sling consists of an eye portion 32 formed of four left and four right lay ropes and a body portion having two legs 36, 38, each of said legs being formed of two pairs of substantially parallel right lay ropes and two pairs of substantially parallel left lay ropes braided together, and an eye portion 40 at the end of each leg. Each eye portion 40 is formed of two left and two right lay ropes which are spliced and either served with wire 42 or provided with a thimble similar to thimble 30.

While one embodiment of my invention has been shown and described it will be apparent that other adaptations and modifications may be made without departing from the scope of the following claims.

I claim:

1. A two-legged sling comprising an eye portion and a body portion extending from the eye portion in two legs, the body portion in each leg being formed of two pairs of substantially parallel right lay ropes and two pairs of substantially parallel left lay ropes braided together, said braiding being maintained in one direction throughout, the eye portion being formed of four left and four right lay ropes.

2. A sling according to claim 1 in which there is an eye portion at the end of each leg, each of said eye portions being formed of two left and two right lay ropes.

3. A sling comprising eight endless units forming an eye portion, two legs leading from said eye portion and an eye portion at the end of each leg, four of said units being made of left lay rope and four of right lay rope, the first eye portion being formed of four left and four right lay ropes, each of said legs being formed of two left lay and two right lay ropes braided together, said braiding being maintained in one direction throughout, each of said last named eye portions being formed of two left and two right lay ropes.

4. A sling according to claim 3 in which the splices for the endless units are in the last named eye portions.

DAVID S. ROBBINS.
